UNITED STATES PATENT OFFICE.

DILLARD L. MAXWELL, OF WIRT, OKLAHOMA, ASSIGNOR OF ONE-FOURTH TO WILLIAM-
SON J. MILBURN, ONE-FOURTH TO LEONIDAS J. MILBURN, AND ONE-FOURTH TO
THEODORE STOCKDELL, ALL OF OKLAHOMA, OKLAHOMA.

CASING-HEAD FOR OIL-WELLS.

1,228,686.

Specification of Letters Patent. Patented June 5, 1917.

Application filed July 5, 1916. Serial No. 107,651.

To all whom it may concern:

Be it known that I, DILLARD L. MAXWELL, a citizen of the United States, residing at Wirt, in the county of Carter and State of Oklahoma, have invented a new and useful Casing-Head for Oil-Wells, of which the following is a specification.

This invention has reference to casing heads for oil wells, and its object is to effect a saving in oil on withdrawing the tools from a flowing well, or in the case of a blow out.

In accordance with the present invention the casing head is provided with an automatically closing valve normally held in the open position against a normal tendency to close with the means for holding it in the normally open position arranged to respond to the withdrawal of the tools from the well or the blowing out of the head of the casing through which the tool-carrying cable ordinarily passes.

The casing head is provided with a diverting neck which is assumed to be properly coupled up to means for controlling the flow, while the automatic means is so arranged as to divert the flow of oil from the end of the casing through which the cable extends, and which end is supplied with a cover which must be removed in order to take out the tools, or which cover is sometimes blown out. It is the removal of such cover, either intentionally or accidentally, that brings about the automatic closure of the passage leading toward such cover and the diverting of the oil to a controllable outlet, which may be, as is customary, in the form of a suitable pipe connected up to the head and supplied with an ordinary cut off valve.

The invention will be best understood from a consideration of the following detailed description, taken in connection with the accompanying drawings forming part of this specification with the further understanding that while the drawings show a practical form of the invention, the latter is not confined to any strict conformity with the showing of the drawings, but may be changed and modified, so long as such

changes and modifications come within the scope of the appended claims.

In the drawings:

Figure 1 is an elevation of the casing head as viewed from one end. 55

Fig. 2 is a section on the line 2-2 of Fig. 1 but drawn on a larger scale.

Fig. 3 is a section on the line 3-3 of Fig. 2.

Fig. 4 is a section similar, but at right angles to the section of Fig. 2, omitting some of the parts shown in Fig. 2 and showing some parts in elevation. 60

Fig. 5 is a section similar to Fig. 4 but showing a different position of certain of the parts. 65

Fig. 6 is a section on the line 6-6 of Fig. 2, but omitting distant parts.

Fig. 7 is a section on the line 7-7 of Fig. 2, but omitting distant parts. 70

Fig. 8 is an inner face view of one of the cap plates.

Fig. 9 is an end view of the diverting or valve member contained in the casing head.

Fig. 10 is a plan view of the valve member. 75

In the drawings there is shown a casing 1 of generally cylindrical cross-section with a neck 2 at one side, another neck 3 diametrically opposite the neck 2, and a third neck 4 at substantially right angles to the diameter representing the longitudinal common center line of the necks 2 and 3. The neck 2 is designed and properly arranged for application to the upper end of the well casing, as 80 is customary. The neck 4 is designed to receive pipe connections for carrying away oil from the head, said pipe connections being customarily provided with a cut off valve, which latter, however, as well as the pipe 90 connections, are not shown in the drawings, since they form no part of the present invention, and are commonly used. The body 1 of the casing is approximately cylindrical but has a slight internal taper from one end 95 toward the other and houses a rotatable member 5 which may be termed a diverting valve. This valve has terminal heads 6, each of which has an axially extended spindle 7. The valve 5 has a central cut out 9 100

extending circumferentially through the peripheral wall of the valve throughout the greater portion of the circumference, but leaving a wall 10 extending the full length of the body of the valve and sufficient to cover that end of the neck 3 where joining the body 1 of the casing. The opposite ends of the body 1 of the casing are closed by heads 11 held in place by screws 12 and carrying central bearing members 13 for the spindles 7, which latter extend through the heads to the exterior thereof and are there axially and cross bored, as shown at 14 and 15, respectively, for the application of a suitable tool or tools, whereby the valve 5 may be turned from the exterior of the casing. Where the wall 10 of the valve stops at the cut-out 9, it is provided with a cable-receiving notch 16.

That end of the neck 3 remote from the body of the casing 1 has a cover plate 17 fitted to it, and this cover plate carries a gland 18 in turn carrying a guide tube 19 extending into the neck through the plate 17. The cap plate 17 also carries a tubular sleeve 20 exterior to and concentric with the tube 19 and also located within the neck 3. Extending through the tube 19 and through the body of the casing, as well as through the valve 5, and also through the neck 2, is a tool carrying cable or rope 21 surrounded by another tube 22 held to the cable by a clamp 23 and set screw 24.

Extending radially inwardly from the inner walls of the sleeve 20 are ears 25 each having pivoted thereto a lever 26 provided with a shorter end 27 extending beyond the end of the sleeve 20 toward the body 1 of the casing. The ends 27 are each rounded on what may be termed the inner edge toward the extremity of said ends, as shown at 28, and these ends are at a slight angle to the respective levers 26, and when the parts are in position the ends 27 diverge toward the neck 2. At the other or upper ends of the levers 26 in the installed position of the casing head, are latch bolts 29 mounted in and slidable through the passages 30 radially positioned in a drop flange 31 on the lower side of the head 17. In matching relation to the passages 30 are sockets 32 in the inner wall of the neck 3 near its upper extremity. The latch bolts 29 serve as means for locking the head 17 in place and in closing relation to the upper end of the neck 3.

Extending in diametrically opposite directions through the neck 3 where joining the body of the casing 1 are slidable latch members 33 each in the form of a bar having one end entering the neck and there upturned, as shown at 34, in the path of the bent lower end of a respective one of the levers 26. A spring 35 bears at one end 35 against the inner wall of the neck 3 and at

the other end against the upturned extremity 34 of the latch rod or bar 33. The bar 33 rests upon and moves lengthwise of the casing 1 exterior thereto and between the guide ears 36 at the corresponding ends of the casing 1. Each head 11 is formed with a slot 37 matching the space between the guide ears 36, so that the bar 33 may slide lengthwise without turning. That end of each bar 33 remote from the upturned end 34 is returned upon itself, as shown at 38, to provide a latch finger 39 extending through a passage 40 in the corresponding head 11 into the interior of the casing 1. The valve 5 is of less length than the interior of the casing 1, so that at each end of the valve between the heads 6 thereof and the heads 11 of the casing 1 are spaces or chambers 41.

Mounted on either or each of the heads 11 at the inner face thereof is a spring 42, preferably though not necessarily a leaf spring. Formed on either or each head 6 is a lug 43 in radial relation thereto and terminating at the end toward the axis of the valve in a toe 44. The radial lug is so arranged that when the valve is turned in the appropriate direction it will engage the spring 42 and bend the latter, as best shown in dotted lines in Fig. 4, thus putting the spring under tension in a manner to have a normal tendency to rotate the valve toward its first position, which position is that shown in Fig. 5, where the wall 10 is in closing relation to the neck 3, but the cut-out 9 then maintains the necks 2 and 4 in constant communication. When the valve 5 is turned into a position putting the spring 42 under tension, the cut-out 9 then places all three necks 2, 3 and 4 in communication, so that the rope or cable 21 may traverse the necks 2 and 3 without interference from the valve. The fingers 39 of the latch bars 33 are normally in the path of the lugs 43 and the bars 33 may be temporarily spread when the valve is turned toward the open position to permit the passage of the lugs 43 by the fingers 39, and when the bars 33 are released the fingers 39 are moved by the springs 35 into the path of the lugs 43, thus locking the valve in the open position, which position is maintained until the valve is released by movement of the bars 33 oppositely away from each other.

In the normal position of the parts the valve is locked open by the fingers 39 and the drilling of the well proceeds in the usual manner, the valve offering no impediment to the movements of the line. In order to introduce the tools, the head 17 already in surrounding relation to the rope 21 and its protecting tube 22, is applied to the upper end of the neck 3 and locked thereto by the latch bolts 29, the valve 5 having been previously locked in the open position.

Assuming that oil is flowing from the well 130

under pressure, as by way of the neck 4, and that it is desired to remove the tools, all that is necessary is to lift the tools by the rope 21 until the rope clamp fastening 5 the rope to the tools or some other part of sufficient size comes into engagement with the curved extremities 28 of the bent ends 27 of the levers 26. The continued upward movement of the rope 21 causes a spreading 10 of the ends 27 and a corresponding outward movement of the bars 33. The spreading of the ends 27 of the levers 26 results in withdrawing the latch bolt 29 from the sockets 32, whereupon the cover 17 is released and 15 rises with the rope and parts carried thereby, the sleeve 20 and levers 26 participating in such movement, but the ends 34 of the bars 33 having been pressed outwardly by the ends 27 of the levers 26, do 20 not interfere with the withdrawal of the tool. The valve 5 having been released by the latch fingers 29 is rotated by the straightening out of the springs 42 into the position shown in Fig. 5, thus closing the 25 neck 3 and preventing any waste of oil therethrough, the oil flowing out through the neck 4 which remains in communication with the neck 2 and therefore with the well casing.

30 Consequently the casing head by the automatic closure of communication between the well casing and the neck through which the tools must be extracted, serves as an oil saver, for otherwise, especially where 35 the oil is issuing under considerable pressure, there is large waste of oil and it is sometimes dangerous to attempt to shut off the flow of oil by trying to close the neck 3.

40 Sometimes the pressure becomes so great as to blow the head 17 off from the neck 3. In such cases the ends 27 of the levers 26 acting upon the rods 33 cause them to move outwardly, thus unlatching the valve and permitting it to rotate to the closed position, the notch 16 then partially encircling 45 the rope or cable or the protecting tube thereof.

50 This closes communication between the well casing and the neck 3, so that even in the case of a blow out there is no wastage of oil and no danger to the workman who would otherwise be compelled to reach the well to close the neck 3. Such attempts in case of blow outs often result in serious 55 injury and even death to the workman.

60 The device of the present invention is entirely automatic in its action so far as the closing of the neck 3 or the diversion of the oil therefrom is concerned, and this closing occurs whether it be required because of an accident or in the event of withdrawing the tools, and in either case no material waste of oil occurs.

65 In order to insure a snug yet free fit of the valve in the body of the casing, the

valve may be slightly tapered and the seat for the valve in the casing may be correspondingly tapered.

Since the action of the casing head in closing the well against wasteful escape of 70 oil is entirely automatic, not only is waste prevented, but danger from fire or explosions is avoided. Still more important is the fact that the automatic action of the casing head permits the drillers and their 75 assistants to leave the well and seek places of safety before withdrawing the tools, and to there remain until the automatic oil saving features of the casing have closed the well and eliminated danger. 80

What is claimed is:—

1. A casing head for oil wells having a passage therethrough for the drilling tools and cable, cut-off means for said passage having means imparting to the cut-off means 85 a normal tendency toward the cut-off position, and holding means for temporarily maintaining the cut-off means out of the path of the drilling tools and cable, said holding means being located in the path of 90 the tools for operation thereby when the tools are withdrawn from the casing head.

2. A casing head for oil wells having a passage therethrough for the drilling tools and cable, means for closing said passage 95 provided with means imparting to the closing means a normal tendency toward the closed or cut-off position, and means for holding the cut-off means against its normal tendency and for releasing it to move under 100 its normal tendency to the closed or cut-off position, said releasing means being located in the path of the drilling tool and constructed to respond to forces exerted on the releasing means by the withdrawal of the 105 drilling tools from the casing head, whereby the cut-off means are automatically released to move to the cut-off position as a tool is lifted from the casing head.

3. A casing head for oil wells provided 110 with means for the passage of oil well tools and an operating cable therethrough, a cut off valve in the casing provided with means for automatically moving it to the cut-off position, and latch means for holding the 115 valve in the open position in opposition to the normal tendency of the automatic means.

4. A casing head for oil wells comprising 120 a casing with oppositely disposed necks for connecting the casing to a well tubing and for the entrance into the casing of an operating cable and tools, a closing head for the second-named neck, a rockable valve in the casing movable to close and open the second-named neck, automatic means for moving 125 the valve to the closed position and yieldable to forces tending to move the valve to the open position, latch means for holding the valve in the open position against the normal tendency of the automatic means, and 130

latch means for holding the closing head for the second-named neck thereto, the two latch means being in coactive relation to cause operative movement of one to produce operative movement of the other latch means.

5. A casing head for oil wells comprising a casing having oppositely disposed necks for attachment to a well tubing and for the entrance of tools and operating cable into the casing and into the well tubing, a rockable valve in the casing having a passage therethrough for the tools and cable and movable into and out of closing relation to the second-named neck, a closure for the second-named neck, latch means for holding the closure to the second-named neck, automatic means for moving the valve to the closed position, and yieldable to forces tending to open the valve, and latch means in coactive relation to the first-named latch means for holding the valve in the open position against its normal tendency to close under the action of the automatic means.

6. A casing head for wells having oppositely directed necks for attachment to the well casing and the introduction of tools and cable into the well through the head with the neck for the introduction of the tools provided with a closure, latch bolts and operating levers therefor carried by the closure and extending into the neck and located in the path of withdrawal of the tools from the neck, the operating means being shaped to be moved on the withdrawal of the tools to release the head, a rockable valve in the casing with its axis of rocking perpendicular to the longitudinal center line of the necks with said valve having an opening for the tools and tool-operating cable, and with parts for closing the second-named neck, automatic means for moving the valve to the closed position and yieldable to forces tending to open the valve, and a latch means for holding the valve in the open position having parts in the path of the latch means for the head of the first-named neck for movement of the second-named latch means to the release position on movement of the first-named latch means to the release position.

7. A casing head for wells, having oppositely directed necks for attachment to the well casing and the introduction of tools and cable into the well through the head with the neck for the introduction of the tools provided with a closure, latch bolts and operating levers therefor carried by the closure and extending into the neck and located in the path of withdrawal of the tools from the neck, the operating means being shaped to be moved on the withdrawal of the tools to release the head, a rockable valve

in the casing with its axis of rocking perpendicular to the longitudinal center line of the necks with said valve having an opening for the tools and tool operating cable and with parts for closing the second-named neck, automatic means for moving the valve to the closed position and yieldable to forces tending to open the valve, and a latch means for holding the valve in the open position having parts in the path of the latch means for the head of the first-named neck for movement of the second-named latch means to the release position on movement of the first-named latch means to the release position, the second-named latch means being also located in the path of the first-named latch means for the action of the second-named latch means by the first-named latch means on the removal of the head from the neck to which it is applied.

8. A casing head for wells, comprising a casing body with aligned necks on opposite sides thereof, one of the necks being adapted to be applied to a well casing and the other neck being adapted to permit the introduction of the well tools and cable through the casing into the well, a cap for the second-named neck, latch bolts on the cap for attaching the latter to the neck, operating levers for the latch bolts having terminal members within the neck in divergent relation one toward the other in a direction toward the well tube and located in the path of parts carried by the cable, other latch members carried by the casing head and having means imparting to them a normal tendency toward each other, and movable in opposite directions in opposition to the normal tendency, said second-named latch members being in the path of movement of the first-named latch members for actuation thereby, a rockable valve in the casing having a passage through it for the cable and well tools and provided with a part movable into closing relation to the second-named neck, spring means tending to move the valve to the closed position with respect to the second-named neck and yieldable to forces tending to rock the valve toward the open position, and means on the valve for engaging the spring means to put the latter under tension, the last-named means being in the path of the second-named latch means for holding the valve in the open position.

In testimony, that I claim the foregoing as my own, I have hereto affixed my signature in the presence of two witnesses.
